US0D1030795S

(12) **United States Design Patent** (10) Patent No.: **US D1,030,795 S**
(45) Date of Patent: ** Jun. 11, 2024

(54) **ELECTRONIC DEVICE WITH GRAPHICAL
USER INTERFACE**

- (71) Applicant: **Apple Inc.**, Cupertino, CA (US)
(72) Inventors: **Arian Behzadi**, San Francisco, CA (US); **Alan C. Dye**, San Francisco, CA (US); **Robert Garcia, III**, San Francisco, CA (US); **Aurelio Guzmán**, San Jose, CA (US); **Nicolas V. Scapel**, London (GB)
(73) Assignee: **Apple Inc.**, Cupertino, CA (US)
(**) Term: **15 Years**
(21) Appl. No.: **29/818,033**
(22) Filed: **Dec. 6, 2021**

(57) **CLAIM**

The ornamental design for an electronic device with graphical user interface, as shown and described.

DESCRIPTION

The file of this patent contains at least one drawing/photograph executed in color. Copies of this patent with color

drawing(s)/photograph(s) will be provided by the Office upon request and payment of the necessary fee.

FIG. 1 is a front view of an electronic device with graphical user interface showing the claimed design; and, FIG. 2 is another embodiment thereof.

The outer broken lines in the figures show an electronic device, and form no part of the claimed design. The other broken lines in the figures show portions of the graphical user interface that form no part of the claimed design.
